J. W. RICHARDSON

TIE FOR COIL SPRINGS

Filed Dec. 31, 1923

FIG 2

FIG 1

INVENTOR

John W. Richardson
BY J. S. Wooster

ATTORNEY

UNITED STATES PATENT OFFICE.

JOHN W. RICHARDSON, OF STRATFORD, CONNECTICUT, ASSIGNOR TO JOHN CHATILLON & SONS, OF NEW YORK, N. Y., A CORPORATION OF NEW YORK.

TIE FOR COIL SPRINGS.

Application filed December 31, 1923. Serial No. 683,602.

To all whom it may concern:

Be it known that I, JOHN W. RICHARDSON, a citizen of the United States, and resident of Stratford, in the county of Fairfield and State of Connecticut, have invented certain new and useful Improvements in Ties for Coil Springs, of which the following is a specification.

This invention relates to a coil spring provided with a binding wire to prevent distortion during tempering. Coil springs are used in large quantities for tire pressure gages, scales, valves, etc., and it is necessary that such springs be of uniform strength and resiliency. An object of this invention is to make a tie for separately and uniformly binding each side of the coil, and more specifically with a single wire in such manner as to keep the binding wires on opposite sides of the coil in their proper spaced relation.

Figure 1 of the drawings is a cross section of the wire on a coil spring.

Figure 2 is a section on the line 2^a—2^a of Figure 1.

The coil spring 10, before being tempered, is bound by the wire 11 preferably of soft iron to prevent distortion of the spring or any of its convolutions in order to insure uniform strength and resiliency in a number of the springs. The single wire 11 has two portions or binding means, 12 and 13, extending along opposite sides of the coil and each separately and uniformly binding the spring. As will be seen from Figure 1, the binding wire is made in a single piece having its end holding portions 14 and 15 bent inwardly to lie against the inside of the coil. The opposite ends of the portions 12 and 13 are similarly bent inwardly as shown at 16 and 17. The connecting portion 18 maintains the parts 12 and 13 in their proper spaced relation and prevents the convolutions getting out of shape or part 12 or 13 slipping with respect to the other part. The wire is of generally W shape. One end of the spring may be bent to form a supporting hook 19 as is customary.

Among the advantages of this invention may be included the simplification of construction whereby a single wire is used in place of the two wires in the prior art. A further advantage resides in the use of the

connecting part 18 for maintaining the portions 12 and 13 on opposite sides of the coil in their proper relation and preventing one sliding out of position with respect to the other in the event of its becoming accidentally loosened. Another advantage is the economy in binding wire since it takes less material to bind the spring according to this invention than under the old way. Another advantage resides in the avoidance of a number of twists in the wire for under this invention only a single bend is made in any portion of the binding wire.

I claim:

1. The combination with a coil spring, of a binding means on opposite sides thereof, each of said means comprising a longitudinal member extending over both ends of the coil and projecting into the same, and means to preserve the spaced relation of said binding means.

2. The combination with a coil spring, of a single binding wire extending around the same and having portions thereof inserted into the coil spring from opposite ends.

3. The combination with a coil spring, of a single binding wire having portions extending along the coil in different spaced portions thereof and bent over each end of the coil to retain the spring compressed.

4. The combination with a coil spring, of a binding wire having portions extending along opposite sides of the same and another portion bent over an end of the coil and connecting said portions on opposite sides of the spring to prevent the same from slipping off.

5. The combination with a coil spring, of a binding wire applied thereon in the general shape of a W and having the sides of said W elongated and bent over.

6. The combination with a coil spring, of multiple spaced binding means extending longitudinally of the spring and having end holding portions bent around each end of the coil, the bent end holding portions extending only part way longitudinally of the coil.

Signed at Bridgeport, in the county of Fairfield and State of Conn., this 22d day of December, A. D. 1923.

JOHN W. RICHARDSON.
